LOCOMOTIVE STOKER

Edwin Archer Turner, Scarsdale, N. Y., assignor
to The Standard Stoker Company, Incorporated,
a corporation of Delaware

Application August 7, 1947, Serial No. 767,033

5 Claims. (Cl. 198—15)

1

My invention relates to a flexible and sectional fuel conveying conduit system and particularly to a stoker conduit system mounted in and extending from beneath the fuel bin of a tender to the firebox of a locomotive.

In the normal operation of a locomotive and tender, relative longitudinal movement occurs therebetween as they travel over curves, and as slack therebetween is taken up in starting and stopping. It is, therefore, essential that the stoker conduit system of a stoker for delivering fuel from the tender bin to the locomotive firebox, be so constructed and mounted as to allow for such relative longitudinal movement.

Various ways have been previously suggested for accomplishing this end, notably by mounting the trough conduit of the stoker on the tender to slide or roll longitudinally with respect thereto, or by providing a telescopic arrangement of the conduit connecting the rigidly mounted tender unit of the stoker and the rigidly mounted locomotive unit of the stoker.

The present invention has for its primary object, the provision of a novel and practical flexible and telescopic stoker conduit system and its arrangement with a locomotive and tender that permits of relative longitudinal movement between parts thereof as relative longitudinal movement between the locomotive and tender occurs.

Another object of the invention is to provide a novel and practical telescopic stoker tender unit, to compensate for relative longitudinal movement occurring between the locomotive and tender, the major portion of the tender unit of the stoker being rigidly mounted on the tender.

Another object of the invention is to provide in a stoker conduit system wherein the forward end thereof is rigidly mounted on the locomotive and the rearward end thereof is rigidly mounted on the tender, a novel and practical construction and arrangement of parts affording the necessary extensibility to compensate for relative longitudinal movement between an inter-coupled locomotive and tender.

Further objects and advantages will become apparent as the following description is read in connection with the accompanying drawings, in which

Figure 1 is a central vertical longitudinal section through adjacent ends of a locomotive and tender with the novel stoker conduit system applied thereto, and shown partly in similar section and partly in elevation;

Figure 2 is a sectional view taken on the line 2—2 of Figure 1;

2

Figure 3 is a sectional view taken on the line 3—3 of Figure 2;

Figure 4 is a plan view of a modification of the telescopic trough portions of the stoker conduit system;

Figure 5 is a central vertical longitudinal section through the modified form of the invention shown in Figure 4;

Figure 6 is a sectional view taken on the line 10 6—6 of Figure 5; and

Figure 7 is a sectional view taken on the line 7—7 of Figure 5.

On Figure 1 of the drawings there is shown an intercoupled locomotive and tender, the locomotive being indicated by the reference character L, the tender by T, and the coupling connection therebetween by C. The coupling C, of any well known construction, permits articulation between the locomotive and tender, and provides for the usual amount of relative longitudinal movement between them.

Fuel is conveyed from beneath the fuel bin 10 of the tender to the firebox 11 of the locomotive by a stoker, indicated generally by the letter S, which includes a conduit system comprising a trough conduit section 12 mounted on the tender, a discharge conduit section 13 rigidly mounted on the locomotive, and an intermediate conduit section 14 connecting the conduit sections 12 and 13. A flexibly connected sectional screw conveyor 15 advances the fuel through the conduit sections 12, 13 and 14.

The trough section 12 includes a relatively short U-shaped front trough portion 16 and a relatively long U-shaped rear trough portion 17 which are telescopically connected, as and for the purpose hereinafter described, to provide for relative longitudinal movement therebetween.

The rear trough portion 17 is preferably of built-up construction including the front cast trough member 18, having an integrally cast base 19; the rear cast trough member 20, having an integrally cast base 21 and a preferably integrally cast gear housing 22; and a bent U-shaped sheet metal trough member 23 received at its opposite ends in and secured in any suitable manner to the cast trough members 18 and 20. It is apparent, however, that the rear trough portion 17 may be formed as an integral unitary casting or built up in any suitable manner, if desired. The rear trough portion 17 is rigidly secured through the base 19 and base 21 to the tender underframe 24 in any suitable manner.

The forward end of the rigidly mounted rear trough portion 17 is slightly enlarged and is ar-

ranged to receive the rearward end of the front trough portion 16. The telescopic connection between the trough portions 16 and 17 provides for relative longitudinal movement therebetween as relative longitudinal movement between the locomotive and tender occurs. Also, as the boiler of the locomotive expands and contracts, the front trough portion 16 slides inwardly and outwardly in the rear trough portion 17.

The sidewalls of the enlarged forward end of the rear trough portion 17 are formed at their upper ends with the inwardly extending flanges forming guideways 25 and 26, as best shown in Figure 2, and are arranged to receive the upper ends of the side walls of the front trough portion 16. It is evident then, that while the front trough portion 16 is free to slide longitudinally with respect to the rear trough portion 17, other relative movement between the trough portions 16 and 17 is arrested.

The front trough portion 16 is provided at its forward end with a hollow spherical shell 27 arranged to be received in the vertically split spherical clamp 28 of the intermediate conduit section 14, forming a universal joint connection between the intermediate conduit section 14 and the trough section 12. The lower end of the discharge conduit section 13 is formed with a horizontally split spherical seat 29, receiving the ball member 30 of the intermediate conduit section 14, to form a universal joint connection between the two conduit sections. The universal joint connections in the conduit system allow for relative angular movement between the conduit sections as relative angular movement between the locomotive and tender occurs in traveling over curving track.

While a crusher (not shown), for reducing oversize lumps of coal to a suitable size for conveyance through the conduit system and for firing, may be mounted on the front wall 31 of the front trough portion 16, as an alternative a crusher may be mounted on the front wall 32 of a U-shaped strap member 33 which is attached in any suitable manner through its side walls 34 and 35 to the side walls of the rear trough member 23. If the crusher (not shown) is attached to the wall 31, then the U-shaped member 33 is dispensed with. The crusher may, therefore, alternatively be secured to the movable trough portion or to the rigid trough portion of the trough conduit section 12.

It will be observed that, in the stoker construction above described, the entire trough 12, including the rigid rear trough portion 17 and the longitudinally slideable front trough portion 16, is open at its top to receive fuel from the bin 10 and the region of the crusher (not shown) is readily accessible should foreign material, such as rail spikes, tramp iron, etc., be caught between the screw conveyor 15 and the crusher or the restricted opening 36 between the trough portion 16 and the spherical shell extension 27.

In Figures 4, 5, 6 and 7 is shown a modified form of the invention, only that portion incorporating structural differences being illustrated. In this construction the bent trough sheet 49 of the rigidly mounted rear trough portion 41, extends forwardly of the trough support casting 42. The front trough portion 43 fits closely about the extension 44 of the trough sheet 49 and is supported therefrom. The means for supporting the front trough portion 43, includes the inturned flanges 45 and 46 extending inwardly and then downwardly from the upper

ends of the respective sidewalls 47 and 48 of the trough portion 43. The inturned flanges 45 and 46 rest on sidewalls 49 and 50, respectively, of the trough sheet extension 44.

- 5 It is evident that while the front trough portion 43 is slideable longitudinally with respect to the rear trough portion 41, other relative movement between the trough portions 41 and 43 is arrested. As in the preferred form of the invention, a crusher (not shown) may be mounted on the front wall 51 of the trough sheet extension 44, or if desired, this wall may be removed and the crusher mounted on the front wall 52 of the longitudinally movable front trough portion 43. A pair of slots 53 and 54 in the forward end of the trough sheet extension 44 provide ways for the arcuate inwardly extending wall 55 to permit longitudinal movement of the front trough portion 43.
- 10 A removable wear plate 56 is secured in any suitable manner on the bottom of the forward end of the trough sheet 49, where most of the wear takes place.

From the foregoing, it is apparent that while 25 the trough conduit section of the stoker is arranged to compensate for relative longitudinal movement between the locomotive and tender, the major portion of the trough is adapted to be rigidly mounted on the tender. Only a small 30 forward portion of the trough is pulled forward or pushed rearward on the tender by the locomotive as relative longitudinal movement between the two vehicles occurs, thereby minimizing the strain imposed on the front sections of the conduit system and on parts of the locomotive as 35 compared to constructions in which the entire trough section is pulled forward or pushed rearward in the tender by the locomotive. At the same time the conduit system dispenses with relatively longitudinally moving parts between the forward end of the trough and the discharge conduit and the entire trough is open to the fuel bin to receive fuel therefrom.

I claim:

- 45 1. A stoker for an intercoupled locomotive and tender, including a fuel discharge conduit section adapted to be rigidly mounted on the locomotive, a fuel receiving conduit comprising a rearward open mouth forwardly opening trough member 50 adapted to be rigidly mounted on the tender and a forward open mouth rearwardly opening trough member mounted telescopically with the forward 55 end of said rearward member to provide for relative longitudinal movement therebetween, said trough members being in axial alinement with their telescoped end portions in circumambient relation, and an inextensible intermediate conduit 60 flexibly connected at its ends with said discharge conduit section and said forward open mouth trough member.
- 65 2. A stoker for an intercoupled locomotive and tender, including a fuel discharge conduit section adapted to be rigidly mounted on the locomotive, a fuel receiving conduit comprising a rearward open mouth forwardly opening trough member 70 adapted to be rigidly mounted on the tender and a forward open mouth rearwardly opening trough member mounted telescopically with and supported by the forward end of said rearward member to provide for relative longitudinal movement therebetween, said trough members being in axial alinement with their telescoped end portions in circumambient relation, and an inextensible intermediate conduit 75 flexibly connected at its ends with said discharge conduit

section and said forward open mouth trough member.

3. A stoker for an intercoupled locomotive and tender, including a fuel discharge conduit section adapted to be rigidly mounted on the locomotive, a fuel receiving conduit comprising a rearward open mouth forwardly opening trough member adapted to be rigidly mounted on the tender and a forward open mouth rearwardly opening trough member mounted telescopically with the forward end of said rearward member to provide for relative longitudinal movement therebetween, the overlapping surfaces of said telescoping members fitting closely one within the other, and inturned flanges formed along the upper edge of the overlapping side walls of the outer of said members and extending over the upper edge of the overlapped side walls of the inner of said members, said overlapping surfaces and flanges arresting any but relative longitudinal movement between said members, and an inextensible intermediate conduit flexibly connected at its ends with said discharge conduit section and said forward open mouth trough member.

4. A stoker for an intercoupled locomotive and tender, including a fuel discharge conduit section adapted to be rigidly mounted on the locomotive, a fuel receiving conduit comprising a rearward open mouth forwardly opening trough member adapted to be rigidly mounted on the tender and a forward open mouth rearwardly opening trough member mounted telescopically within the forward end of said rearward member to provide for relative longitudinal movement therebetween, the overlapping surfaces of said telescoping members fitting closely one within the other, and inturned flanges formed along the upper edge of the forward portion of the side walls of said rearward trough member and extending over the upper edge of the side walls of said forward trough member, said overlapping surfaces and flanges arresting any but longitudinal movement therebetween.

dinal movement of said forward trough member with respect to said rearward trough member, and an inextensible intermediate conduit flexibly connected at its ends with said discharge conduit section and said forward open mouth trough member.

5. A stoker for an intercoupled locomotive and tender, including a fuel discharge conduit section adapted to be rigidly mounted on the locomotive, 10 a fuel receiving conduit comprising a rearward open mouth forwardly opening trough member adapted to be rigidly mounted on the tender and a forward open mouth rearwardly opening trough member mounted telescopically about the forward end of said rearward member to provide for relative longitudinal movement therebetween, the overlapping surfaces of said telescoping members fitting closely one within the other, and inturned flanges formed along the upper edge of the side walls of said forward trough member and extending over the upper edge of the forward portion of the side walls of said rearward trough member, said overlapping surfaces and flanges arresting any but longitudinal movement of said forward trough member with respect to said rearward trough member, and an inextensible intermediate conduit flexibly connected at its ends with said discharge conduit section and said forward open mouth trough member.
